MACHINE FOR COMPOSING LITHOGRAPHIC PRINTS

René Louis Romain Robert Geirnaert,
Brussels, BelgiumApplication November 21, 1936, Serial No. 112,021
In Germany December 3, 1935

6 Claims. (Cl. 197—84)

This invention relates to a machine for composing lithographic prints by direct grease printing on a transfer paper and more particularly relates to mechanism for obtaining "justification", that is to say, adjustment of line to a predetermined length.

The invention is applicable to any machine having proportional spacing movement, that is to say, mechanism which will permit within predetermined limits a spacing movement of infinitely variable dimension. For that reason the invention is particularly applicable to the invention forming the subject of my co-pending application for patent, Serial No. 112,020 and may be incorporated therewith.

It is an object of this invention to adjust the spacing between subsequent words of a type-script line to justify or even the line by subdividing the total spacing width into equal spacing units and to insert widths according to these units between each two subsequent words of the line.

It is a further object of this invention to utilize the width of space dividing elements of adjustable width to effect the subdivision of the total spacing, these elements being brought into a spacing chamber from a magazine in a number corresponding to the number of spacings required.

It is a still further object of the invention to feel, store and transfer the width of these spacing units and to transfer them to the escapement of the machine carriage and to control its movement so that equal spacing units will be inserted between each two subsequent words when the line is being written, thus justifying or evening the line.

Other objects of the invention may be seen from the following description and the accompanying drawings.

In the drawings affixed hereto and forming part of the specification, the invention is illustrated by way of example. It will be readily understood, however, that my invention is not limited to this example and that my invention may be embodied in other forms without departing from the principle underlying my invention and from the ambit of my appended claims.

In the drawings:

Fig. 1 is a perspective front view of a typewriter according to this invention.

Fig. 2 is a perspective rear view of this typewriter.

Fig. 3 is a sectional elevation of a space subdividing blade magazine,

Fig. 4 is a view, on an enlarged scale, of the blade magazine and of the conveying means for conveying the blades from the blade magazine to the spacing chamber,

Fig. 5 is a perspective side-view of the spacing chamber,

Fig. 6 is a perspective view of the means for feeling, setting and storing the spacing width units,

Figs. 7 to 11 are diagrammatic views showing the various steps for bringing the space determining blades from the magazine to the spacing chamber, and for determining the space width unit,

Fig. 12 is a front view of a scale used for determining the subdivision of the total spacing width,

Fig. 13 is a perspective view on an enlarged scale of the cams controlling the movement of the conveyer means shown in Fig. 4.

11 is the base of a typewriter provided with keys 4, types 5, a carriage 6, the elements, mechanisms or drives of which, in so far as they are not concerned with this invention, are of any convenient or known construction and thus are not shown in detail on the drawings.

183, 183' are wedge-shaped blades which, as later on will be described in detail, are the governing means for evenly subdividing the total of the word spacing of a type-script line which 30 line is to be justified, or rendered even, by properly spacing the words.

The blades are arranged in two tiers, one upper tier of blades 183 and one lower tier of blades 183'. The blades are arranged for co-operation 35 in pairs (Figs. 7 to 11), and the blades of each pair may be displaced, one blade in relation to the other, by sliding them on their inclined wedge-shaped surfaces; thus varying the width of each blade pair and adapting the total width 40 of the blade pairs to specific purposes, as will be set forth later on.

The blades 183 and 183', by means of flanges 283 and 283' respectively, which flanges protrude from their edges opposite to their wedge-shaped 45 surfaces may be slid within grooves 284, 284' respectively, of an upper (184) and a lower (184') jaw-like wall structure, both structures thus defining a storage chamber or magazine from which the blades may be moved to a spacing chamber adjoining the magazine and which spacing chamber is likewise formed by an upper (196) and a lower (196') jaw-like wall structure provided with grooves 296 and 296' respectively, Fig. 5, which correspond in shape and configura- 55

tion to the grooves 284 and 284' and in which grooves the blades may be slid from one chamber to the other or vice-versa, as will be more fully described later on.

5 The spacing chamber (196, 196') may be laterally confined by means of two hook-like shutters 176 and 177 which may be moved into and out of the spacing chamber. Shutter 177 is slidably mounted with its head 422 on a bar 178 and may be adjusted thereon by means of a set screw 278. Bar 178 is pivoted in two brackets 179 secured to frame bar 300 of the carriage 6 of the machine and may thus follow any tilting of shutter 177. Spring 180, which is extended 15 between bar 178 and carriage bar 300, urges the lower edge of bar 178 against a stop 181 arranged at one of the brackets 179, and simultaneously urges shutter 177 out of the spacing chamber.

Shutter 176 is secured to a bar 276 which is 20 slidably arranged within and traverses the machine and bears at its other or front end a push-button 235. Shutter 176 is further provided with a pin 182 which extends laterally and is arranged opposite a nose 277 of shutter 177. 25 When push-button 235 is pulled to the front (of the machine) pin 182 engages nose 277 and both shutters 176 and 177 are moved simultaneously into the spacing chamber. Shutter 176 will lie between the entry side of spacing chamber 196, 30 196', and the exit of the magazine 184, 184', see Figs. 6, 10 and 11 and by means of its upper edge will bear against abutment 185 secured to the upper wall structure 184. Shutter 176 and bar 276 will be kept in this position by the friction 35 with which bar 276 is mounted in the frame of the machine. When push-button 235 is pushed back, shutter 176 will be moved directly, and shutter 177 by means of spring 180, out of the spacing chamber.

40 A scale 172 is secured to the frame of the machine by means of a bracket 173. A pointer 175 co-operating with scale 172 is carried by a rail 174 secured to frame bar 300 of the carriage and may be adjusted as to its position relative to the 45 carriage by displacing it within a slot 274 provided within the bar 174, for thus determining what right hand margin should remain on the paper on which the script is to be written.

Scale 172, as shown in Fig. 12, is provided with 50 three graduations: a top graduation (272) which is made in Ciceros (twelve point type); a medial graduation (372), the number of the marks of which corresponds to the total number of the blade pairs or spacing elements which may be 55 stored within the magazine, e. g. twelve pairs, and the distance of which marks equals the width of the individual blade pairs in their undisplaced narrowest position (Fig. 7); and a base graduation (472) the number of the marks of 60 which likewise corresponds to the aforesaid blade pair number, and the distance of which marks equals the width of the individual blade pairs in their utmost displaced, widest position, Fig. 11 showing an intermediate position.

65 Scale 172 may be used for an initial determination of the total word spacing width which is available for distribution among the interstices of the words which follow each other in a line to be justified or evened.

70 For this purpose, a rough draft of the line is written by means of the machine, putting one word immediately after the preceding, leaving out the spaces. During this writing operation the pointer or index 175 will move together with the 75 machine carriage to the left; and when the draft

of the line has been finished, the pointer will show in the top scale the number of types in Ciceros, or the total spacing width which remains from the end of the text to the right hand margin of the line. The position of pointer 175 in 5 relation to the other scales 372 and 472 shows whether or not the type script line may be appropriately filled with spaces. Let us assume, pointer 175, after the draft of the line had been written, has reached the position indicated at 10 A in Fig. 12. As this position lies beyond scales 372 and 472, it may be seen that the line residue cannot be filled up with spaces how wide the blade pairs 183, 183' might be expanded. Thus, the line should contain, for instance, one or two 15 words more. After having been modified correspondingly, the line may consist of ten words and the pointer 175 may now reach position B. This position in scale 372 corresponds to a line residue of only four blade pairs, and as for ten 20 words, nine spaces are necessitated, it shows that no sufficient number of blade spaces is available. The text must be split otherwise, for instance, by taking one word to the next line or by splitting one word. After renewed modification of 25 the line, pointer 175 may point at C and nine spaces may be needed. As this position is intermediate 9 grades of scale 372 and of scale 472, it is evident that nine blade pairs may be expanded to fill the line residue or total spacing 30 width, each blade pair after expansion defining the width of one space and the total spacing width being subdivided by the blade pairs into nine spaces of equal width.

The pointer thus shows on the scales when the 35 number of blade pairs is smaller than that which is required, or when the blade pairs cannot be expanded to such an extent as to fill the required spacing and when thus the line must be split otherwise, for example, by taking one or more 40 words from the line to the next line, or by adding one or more words to the line from the next line and/or by splitting a word, or splitting it otherwise than before, or the like, just as it is done with type-setting operations.

45 After this determination, the reading of pointer 175 will be taken to bar 178, and shutter 177, by means of its head 422, is correspondingly set. For this purpose bar 178 is likewise provided with a scale, preferably graduated in Ciceros, a part 50 of such scale being indicated at 378. By shifting the head 422 of shutter 177 along the scale and adjusting it in a position corresponding to the reading of pointer 175, the distance between shutter 177, which is movable together with the carriage, and shutter 176, which is stationary in 55 relation to the machine frame, may be set to equal the width of the total spacing which is required.

Upper and lower wall structures 184 and 184' 60 respectively, are secured to the frame of the machine. Two brackets 186 are provided at the lower structure close to outer ends of the chambers 184, 184' and 196, 196' respectively in which brackets a rod 187 is slidably arranged.

65 A guide plate 188 having a hub 1188 is secured to rod 187, which guide plate enters the chambers 184, 184' and 196, 196' at the left hand side of blades 183, 183', as may be seen in Fig. 2. If guide plate 188 is pushed laterally to the right, 70 Fig. 1, by the operation of an index arm 195 connected to a rock shaft 191, in turn connected to a crank 194, and, by means of link 193, to a tongue 2188 of plate 188, thus from chamber 196—196' back to chamber 184—184', the fore- 75

most blade pairs will always be pushed into a definite position within chamber 184—184'. Secured to guide plate 188, by means of rod 189, is a second guide plate 190 of T-form which is arranged at the other side of the blade pairs and at a distance from plate 188 which is the sum of the total width of all but one of the unexpanded blade pairs and of the length of the stroke which pushes the foremost blade pair from 10 chamber 184—184' to chamber 196—196'.

When blade pairs 183, 183' are pushed from the magazine 184, 184' into the spacing chamber 196, 196' by means about to be described guide plate 188 will be taken along with said plate 15 pairs, and in front of them, and, as may be seen from Figs. 1, 8 and 9, will cause the index 195 to move over its scale 295 thus indicating the number of blade pairs which have been shifted into spacing chamber 196, 196'. Pressing by hand 20 index 195 to its zero position will, by means of its lever system cause guide plate 188 to shift the blade pairs from chamber 196, 196' back into chamber 184, 184', and simultaneously, bring the blade pair which is in front and next to guide 25 plate 188 into a definite position from which it may be brought into chamber 196, 196'. Conversely, when the foremost blade pair is pushed from chamber 184—184' to chamber 196—196', it takes guide plate 188 along with it and in front 30 of it, Figs. 7 and 8, whereas guide plate 190 follows and pushes the blade pairs remaining in chamber 184—184' towards chamber 196, 196' to the extent that blade pairs have been moved from chamber 184, 184' to chamber 196, 196'; 35 the foremost blade pair, facing chamber 196, 196' of the set, thus is always brought into one definite position from which it may be pushed into the spacing chamber 196, 196'.

The mechanism for pushing the blade pairs 40 from chamber 184, 184' into chamber 196, 196' comprises two push levers 198, 199, arranged above and below chamber 184, which with their rake-like heads 298, 299 may enter apertures 398, 399 provided within the top structure 184 45 and base structure 184' of this chamber. The push levers are pivoted at 200 and 200' to a slide member 201 of T-form which is slidably arranged on a slide bar 202 mounted in brackets 203 which are secured to a stationary housing or wall structure 50 303 of the machine.

The slide member 201 is connected by means of link 210, crank arm 211, and rock shaft 212 to a key or operating lever 213, (Figs. 2 and 4), which key, by means of spring 214 (Fig. 1), is urged into its uplifted position, thus holding, 55 by means of linkage system 212, 211, 210, slide member 201 in its rest or zero position shown in Figs. 2 and 4. Push levers 198, 199 are extended beyond their pivots and bear at their rear ends 60 hubs or lugs 204, 304, provided with bores within which rods 205, 305 (Figs. 4 and 13) may slide. Fast to housing 303 are two top cams 206, 207, and two base cams 208, 209 at both sides of push levers 198, 199 which with their lower cam surfaces 65 co-operate, alternatingly at either side, with rods 205 and 305. Rods 205 and 305 are held by the weight of the front part of levers 198, 199 against the cams. When starting from the rest position, shown in Figs. 4 and 13, rods 205 and 70 305 are contacting the front cams 207, 209 respectively.

When lever 213 is depressed and slide member 201 thus advanced to the left, Fig. 4, rod 205 will be on the lowermost part 501, Fig. 13, of cam 75 207, whereas rod 305 will be on the highermost

part 507 of cam 209 Fig. 13 and the rake-like heads of push levers 198, 199, will be separated away from any contact with the blades. As soon as both rods 205, 305 reach the upward sloping part 502 of cam 207 and the downward sloping 5 part 508 of cam 209 respectively, the push lever head 298 will be lowered and the push lever head 299 will be raised and both heads will be moved through the chamber openings 398, 399 (Fig. 4) and behind the foremost blade pair 183, 183' 10 (Fig. 7), which had been positioned at the proper place in chamber 184, 184' by means of guide plate 188 when it had been pushed back by link 193 at its foregoing return stroke.

The blade pair is seized by push heads 298, 15 299, and pushed at the entrance of chamber 196, 196' (Fig. 8). The penetration movement of the push heads behind the positioned blade pair will be facilitated by means of indentations 383, 383' which are provided at the top edges of the blades 20 (Figs. 6 and 7). The advancing blade pair 183, 183' takes along with it the guide plate 188 in front of, and by means of, the first blade pair 183, 183' and also the guide plate 190 which by means of rod 189 is movable with guide plate 188, 25 whereas the blade pairs which are remaining in chamber 184, 184' are pushed by guide plate 190 and are advanced Figs. 8 and 9 thus bringing the next blade pair into that position from which it may be pushed by the push lever heads 298, 30 299 at their next operation.

When the advance movement of slide member 201 nears its end, rods 205 and 305 will reach the oblique surfaces 503 and 509 respectively of cams 207 and 209, Fig. 13, and thus be pushed 35 to the rear, so that with the return stroke of slide member 201, which is caused by spring 214, rods 205 and 305 will be in co-operation with cams 206 and 208 respectively. Immediately after the beginning of the return stroke of slide 40 member 201, rod 205 will reach the lowermost part 505 of cam 206, and rod 305 the uppermost part 511 of cam 208, and the push lever heads 298, 299 will thus be lifted out of contact with the blades, opened, and disengaged from seizing 45 any blades on their return stroke. The push lever heads will remain uplifted until rods 205, 305 will reach the oblique surfaces 506 and 512 respectively of cams 206 and 208, which surfaces will push rods 205 and 305 lengthwise to the front, 50 into contact with the lowermost surface 501 of cam 207 and the uppermost surface 507 of cam 209 respectively.

This play will be repeated and the key 213 depressed each time when a word of the rough 55 draft has been written, thus bringing into chamber 196, 196' a number of blade pairs which corresponds to the number of spaces which are to be inserted between the subsequent words of a script-line (Fig. 10). This depression of key 60 213 will not shift the carriage.

The arrangement of the expansion of the blade pairs for filling the total spacing width will be described now.

Two guide rods 306, 307 are mounted in bars 65 308, 309 (Figs. 1 and 5) secured to the machine base. Top structure 196 and base structure 196' are arranged to slide on these guide rods 306 and 307 and may be reciprocated by means of slot bar 312, pivoted at 320 to the machine frame, 70 and links 313, which slot bar may be controlled by means of slot guide members 317, 318, and control lever 197 which is pivoted at 316 to the machine frame.

By pulling knob 235, bar 276 will pull shutter 75

176 into the space between chambers 184—184' and 196—196', Figs. 10 and 11, and pin 182 will abut tongue 277 of shutter 177 and thus take shutter 177 along with it, and shutter 177 will 5 now lie at the left end within chamber 196—196', the distance between shutters 176, 177, defining the total spacing width, as described above.

If lever 197 will now be depressed, top structure 296 and base structure 296' will be moved 10 towards each other and will cause the wedge-like blades of the upper tier and those of the lower tier to displace themselves, one tier towards and between the other tier. Due to their wedge-like surfaces, the blades of the upper tier and those 15 of the lower tier will slide by means of their complementary oblique surfaces in relation to each other and all blade pairs will expand their width until the blades of both tiers together will have filled up the space between shutters 176 20 and 177. In this way, the available total spacing is subdivided among the blade pairs and into a number of equal units which corresponds to the 25 number of interstices between the subsequent words of the line, the individual width or spacing unit being the same for all pairs, and the width of each pair representing the unit of spacing width which is to be inserted between subsequent words of the line.

This spacing width unit will be transferred to 30 the carriage escapement in the following way:

A push button 216 at the front of the machine (Fig. 1) is connected, by means of a rod 215 (Figs. 2 and 6) traversing the machine frame, to a head 217, which is slidably arranged in guides 35 401 (Figs. 2 and 6) of a bracket 402 secured to the base frame of the machine. Head 217 is provided with an oblique slot 403 into which slot a pin 404 protruding from the lower surface of a guide member 218 enters, Fig. 6 showing both 40 elements lifted from each other for a better understanding only. Guide member 218 carries, by means of a rod 219, a feeler head 419, which feeler head in its rest position reaches a vertical plane containing the left hand surface of shutter 177, 45 as indicated in Fig. 10.

The lower blades 183' are provided with lateral lugs 236 and when, by means of structures 196, 196', the blades of the pairs have been displaced toward each other or expanded their width 50 (Fig. 11, and Fig. 6 blade pair B), these lugs will reach into the path of the feeler 419, whereas the feeler may pass just above the lugs, Fig. 3, when the blades of a pair are still in their original undisplaced position in chamber 184, 184' (Fig. 56 6, blade pair A) or in chamber 196, 196'. The feeler head 419 may pass through an opening 430 of shutter 176, when this shutter is closed, Fig. 6. As, with the displacing of both tiers of blades 60 towards each other, the lower blades will be shifted to the left (Figs. 6 and 11) in relation to the upper blades and in relation to the surface plane of shutter 176 facing the blades, the feeler 419, when button 216 (Fig. 6) is pulled, may now move a short path to the left, until it contacts lug 65 236 of the lower blade 183' next to closed shutter 176, see Fig. 11. As the length of this path is dependent upon the width of the compressed blade pair, the feeler will thus register the width of the spacing unit which is to be inserted 70 between two subsequent words of the script line, and the width will be stored as long as button 216 remains in its position.

The width of the spacing unit thus having been stored, the blades may be reset. For this 75 purpose, the structures 196, 196' will be lifted by

means of lever 197; the shutters 176, 177 opened by pushing button 235; and the blade pairs 183', 183' re-shifted from chamber 196, 196' into chamber 184, 184' by depressing lever 195; and the blade pairs are thus brought into the position shown in Fig. 7.

Head 218 is further provided with a slotted slide guide 222 in which guide a tongue 223 may slide which bears at its lower surface a protrusion 405 and a pin 406. This pin 406 engages a slot 407 of a lever 224 pivoted at 408 to the base frame 11 of the machine. A nose 409 of lever 224 is in operative connection with a bar 227 which traverses the machine, pivots about pivot 9, and bears at its front end a key 226. A bar 2 in the form of a rectangular frame is arranged within the base frame 11 of the machine and is likewise pivoted at 9. This bar effects the spacing movement of the carriage by means of an escapement clutch 32. This escapement clutch 32, which may grip or release a rail 66 secured to the carriage, is stationary with the machine frame, may however, when its grip is released, be displaced a controlled distance along rail 66, and when its grip is closed, may move together with the rail or the carriage in accordance with the distance to which it had been set. This displacement may be effected by means of bar 2, rod 38, cam mechanism 410, 411. For a more detailed disclosure and description of the escapement clutch and its function and control, reference is made to my copending application Ser. No. 112,020 filed on Nov. 21, 1936. This clutch when controlled to grip the rail 66, as described in my co-pending application Serial Number 112,020, may move together with the rail 66 or the carriage for an escapement step until it will abut against a stop 40 secured to the machine frame.

The distance between stop 40 or the point where the common movement of clutch 32 and rail 66 is stopped, and the right hand edge of the escapement clutch 32 at the point where the clutch grips rail 66 and from where the common movement of clutch 32 and rail 66 starts, Figs. 2 and 6, defines the spacing width which may be utilized for insertion between subsequent words.

This spacing width may thus be controlled by two means. First escapement clutch 32 may be slid in the direction along rail 66 by means of member 410 to which it is operatively connected by means of pin 411 and an oblique slot 412 and which member is operated by bar 2 through the intermediary of rod 38 downwardly extending from member 410 and contacting bar 2. When front bar 2 is depressed by one of the type keys 4, or one of the spacing keys 234, 233, 230, 231, 232, rear bar 2 will raise cam 412, and clutch 32, which has released its grip, will thus be shifted to the left in relation to rail 66, Fig. 2, a distance which depends upon the stroke or lift of rear bar 2.

The setting of clutch 32 in relation to rail 66 may be controlled secondly by tongue 223 which may be displaced into the path of escapement clutch 32, and against which tongue, the right hand edge of clutch 32 will abut when escapement clutch 32 will be moved by means of bar 2—by the intermediary of lever 224, bar 227 and key 226—and which tongue, under the control of feeler 419 as described above, and, by the movement of head 218, has been positioned lengthwise in relation to the carriage, see also Fig. 6.

Lever 227 carries a lug 229 (Fig. 1) for engaging bar 2, which lug 229, when key 226 is oper-

ated, will, according to its length, give to bar 2 a stroke of definite length and will through the intermediary of this bar, rod 38, cam mechanism 410, 411, 412, displace clutch plate 32 on rail 66 5 to an extent which defines the spacing width corresponding to the width of an undisplaced blade pair 183, 183', which width is to be considered as the normal spacing width. Key levers 230, 231, 232, 233 and 234 which are pivoted 10 likewise about pivot bar 9, have lugs to engage bar 2, which lugs are of such various lengths as to give spacing widths as follows: key 230: Cicero; key 231: em-quad; key 232: er-quad; key 233: thin space; key 234: half thin space. 15 These levers are not associated with the mechanism for adjustment of the line; they operate by means of bar 2 and rod 38 for moving the escapement clutch 32 away from abutment 40 for a distance determined by the length of their 20 respective lugs. If, however, key 226 is manipulated, this key by means of bar 227, lug 229 and bar 2, will operate bar 38 and by means of the rear end of lever 227, lever 224 thus bringing escapement clutch 32 into a distance from stop 25 40 which corresponds to the greatest spacing unit which by operation of key 226, might be inserted between each two subsequent words of the type-script, and which spacing unit will then be determined, set, and stored as above disclosed according to actual conditions and by the setting 30 of tongue 223 in relation to clutch plate 32.

When the type-script line is being written, key 226 will be manipulated each time a word had been written. As soon as the line has been completed, button 216 may be pushed to its rest position, and thus, the feeler will be likewise restored to its zero position and the machine cleared for the operation of the next line.

The operation of the machine thus comprises 40 in extenso the following steps:

1. The total length of the words composing the line is determined as follows: The carriage is at its starting point. Pointer 175 is moved in slide guide 274 until it is in juxtaposition with the 45 zero point of scale 172. A rough draft of the line is written, the words following each other without spaces. Pointer 175 shows on scale 172 the number of Ciceros required. The head of shutter 177 is displaced and set on scale 178 at 50 a distance, equal to the number of Ciceros afore-determined on scale 172, from the zero point of this scale which corresponds to the position of shutter 179.

2. The total length of the words and the ap- 55 pertaining total spacing width are examined by means of scales 212, 372, 472 and the composition of the line is eventually changed.

3. When writing the rough draft of the line, key 213 is depressed each time when a word has been written; or when the number of required spaces has been ascertained otherwise, by depressing key 213 as often as there are interstices between each two subsequent words. Depression 60 of key 213 does not effect a displacement of the carriage, but causes the blade pairs 183, 183' to be assembled within the spacing chamber 196, 196'.

4. The blade pairs assembled within the spacing chamber will be confined between shutters 177, 179, which will now be closed and the blade tiers are displaced, one blade tier in relation to and towards the other, and the displacement or spacing unit felt; feeler 419 set and stored by 70 manipulation of button 216, and the blades then 75

restored into magazine 184, 184' by operation of lever 197, key 235, and lever 195.

5. The line will now definitely be written, and the afore determined space units are inserted by manipulation of key 226 while writing the line 5 and between each two subsequent words and the feeler then cleared by manipulation of button 216.

I claim:

1. A spacing mechanism for a typewriter for 10 the production of type-script for lithographic duplication, said mechanism including a spacing chamber, means for setting the width of said spacing chamber in accordance with the total spacing width of a type-script line, a magazine 15 adjacent to said spacing chamber, a plurality of divisor elements of modifiable thickness within said magazine, means for conveying said divisor elements from said magazine into said spacing chamber, a key for operating said conveying 20 means, said conveying means adapted to convey one divisor element at each operation of said key and in accordance with the number of spaces of said type-script line, means for evenly expanding said divisor elements until full occupancy 25 of the set width of said spacing chamber, said divisor elements thus defining equally wide spacing units, and means for transferring the width of the spacing unit to a space varying device of the carriage escapement. 30

2. A spacing mechanism as set forth in claim 1, said divisor elements comprising each a pair of complementary wedge-shaped blades, the blades of said pairs being arranged in an upper tier and a lower tier respectively, guiding means at the top structure and at the base structure of said spacing chamber and of said magazine, the blades of said upper tier suspended from said top guiding means, the blades of said lower tier supported by said base guiding means, the top 40 structure and the base structure of said spacing chamber forming jaw-like members, means for reciprocating said jaw-like members, one in relation to the other. 45

3. In a spacing mechanism as set forth in claim 1, indicating means adapted to indicate towards the end of a draft line typed without spaces the total spacing width of said line, said chamber width setting means comprising a pair of shutters adapted to be moved into and withdrawn 50 from said spacing chamber, one of said shutters being displaceably arranged in relation to the other for the purpose of adapting their distance to the total spacing width of said line. 55

4. A spacing mechanism for a lithographic-type-script typewriter, said mechanism including a stationary spacing chamber, a stationary magazine adjacent to said spacing chamber, a plurality of pairs of complementary wedge-shaped spacing blades, means provided at said magazine 60 and said chamber for slidably supporting the blades of said blade pairs in two tiers, a conveying lever, conveying means adapted to be operated by said conveying lever and to convey any predetermined number of said blade pairs 65 from said magazine into said spacing chamber,—one pair at each operation of said conveying lever in accordance with the number of spaces of a type-script line,—two shutters associated with said spacing chamber, one of said 70 shutters displaceable in relation to the other for the purpose of adapting their distance to the total spacing width of said type-script line, both said shutters adapted for movement into and withdrawal from said spacing chamber and for 75

confining at both sides within said chamber said predetermined number of blade pairs conveyed into said chamber, means associated with said spacing chamber for displacing the blades of one of said blade tiers in relation to and between the blades of the other of said tiers for filling the width between said shutters, and for thus expanding the width of said blade pairs as to correspond to the width of the space units of said line, and means for transferring said space unit width to a space varying device of the carriage escapement.

5. A spacing mechanism as set forth in claim 4, said mechanism further including two guide plates, one solidary to the other, and arranged one in front of said blade pairs and the other at their rear, and means for shifting said guide plates in the direction from the spacing chamber to the magazine.

6. A spacing mechanism as set forth in claim 4, said means for transferring said space unit width to a space varying device of the carriage escapement comprising a key operated feeler adapted to be displaced in accordance with the expansion width of one blade pair, a displaceable abutment at the stationary part of the typewriter, carriage spacing means, and intermediary mechanism adapted to displace said abutment relatively to said carriage spacing means in accordance with the displacement of said feeler and said expansion width, said abutment adapted for transitory co-operation with the typewriter escapement.

RENÉ LOUIS ROMAIN ROBERT
GEIRNAERT.
